UNITED STATES PATENT OFFICE

123,559

DESIGN FOR A DRESS ENSEMBLE

Anna Louise Siverts, New York, N. Y.

Application July 31, 1940, Serial No. 94,077

Term of patent 3½ years

To all whom it may concern:

Be it known that I, Anna Louise Siverts, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design,

Fig. 2 is a rear view thereof,

Fig. 3 is a front view of the dress member of the ensemble shown in Figs. 1 and 2, and

Fig. 4 is the rear view of Fig. 3.

The characteristic feature of my design resides in the combination on the dress ensemble disclosed of the specific duo-colored waist portion of the dress member of the ensemble together with the specific bolero and belt as shown.

I claim:

The ornamental design for a dress ensemble, substantially as shown and described.

ANNA LOUISE SIVERTS.
